UNITED STATES PATENT OFFICE.

GEORGE A. RICHEY, OF URBANA, OHIO.

OPEN FIREPLACE.

Application filed September 28, 1923. Serial No. 665,324.

To all whom it may concern:

Be it known that I, GEORGE A. RICHEY, a citizen of the United States, residing at Urbana, in the county of Champagne and 5 State of Ohio, have invented certain new and useful Improvements in an Open Fireplace, of which the following is a specification.

My invention relates to an improvement in 10 open fire-places, and my general object is to provide a simple and effective device adapted to be installed in either new or old fire places for the prevention of the escape of soot into the room and which will permit 15 accumulating soot to be gathered and stored for convenient removal and which will also permit regulation of the up draft and prevent back drafts. Thus in the accompanying 20 drawings, Fig. 1 is a horizontal section of a fire place embodying my improved device, this view being taken in line 1—1 of Fig. 3, and Fig. 2 is a similar section in a lower plane on line 2—2 of Fig. 3. Fig. 3 is a front elevation of the fire place and 25 Fig. 4 is a vertical section centrally through the fire place. Fig. 5 is a vertical section of the fire place on line 5—5 of Fig. 4 looking toward the rear. Fig. 6 is a perspective view of the throat and damper 30 member. Fig. 7 is a perspective view of the removable rear wall which is used with the throat member in forming a receiving compartment within the fire place. Fig. 8 is a vertical section corresponding to Fig. 4 of a slightly modified form of my invention. 35

One of the objectionable features of an open fire place is the escape or dropping of soot from the flue or chimney into the room, especially when the fire place is not 40 in use or when down drafts occur.

The present invention is designed to prevent the escape of soot by a specially constructed throat member 2 and a false rear wall 3, together with a pair of associated 45 dampers 4 and 5 pivotally hinged or mounted within or upon the discharge pipe or elbow 6 connected with the converging upper end 7 of throat member 2.

The device is particularly applicable to 50 the remodeling of old fire places although obviously it may be also installed within a new fire place. Thus it is customary in building fire places to provide a tapering smoke chamber 8 above the open fire place 55 9. In installing my device I project the

converging portion 7 of throat member 2 into smoke chamber 8 and support the lateral base flanges 9' of member 2 upon the brick walls 10 at opposite sides of the fire place. A portion of the lateral flange 11 at 60 the rear of throat member 2 is bent upwardly and downwardly to form a longitudinal groove 12 adapted to receive and hook over the upper straight edge 14 of a metal plate which forms false rear wall 3 of the fire place. This plate or wall 3 is spaced apart 65 a few inches from the main rear wall 15, the plate having for this purpose angularly bent flanges 16 extending its full height at its opposite vertical edges. The fire-brick 70 lining 17 of the fire place extends to and encloses the laterally-extending base flanges 16 of plate 3 and this brick lining 17 is also built up across the front of plate 3 if the fire place is to be used for hard fuel. However, if a gas burner is installed instead, the lining of brick in front of plate 3 may 75 be omitted and the plate itself formed or shaped in any suitable way to permit the use or installation of a gas burner within 80 the fire place. A vertically inclined strip 18 may also be affixed within the vertical space at the rear of plate 3 to form a flaring compartment adapted to collect soot dropping from the smoke chamber 8 and 85 flue 19 above, and an opening or door 20 may be provided in plate 3 opposite the converging end of the soot compartment to permit the removal of the soot from the compartment. 90

The soot from the chimney or flue 19 is 95 prevented from passing into and out of throat member 2 by reason of the construction of this member and the working arrangement of the two dampers 4 and 5 respectively. Thus I prefer to use a relatively small pipe or elbow 6 of approximately the same cross-section as flue 19 and to turn this elbow horizontally toward the rear within smoke chamber 8 so as to baffle a down draft, 100 and damper 4 is pivoted within the vertical straight portion of the pipe or elbow to permit convenient regulation of the up-draft, although when completely shut it also serves to prevent a back-draft. The rear discharge 105 end of the elbow is adapted to be opened or closed by hinged damper 5 and when this damper is closed the soot is absolutely prevented from entering the elbow. Damper 5 is also hinged or supported to turn upon a 110

vertically-inclined axis so that it may open by gravity and also so that it will fold and lie in a vertically-inclined plane beneath the projecting top of the horizontal part of the elbow and not collect soot upon its face or edges when closed. Rods 21 and 22 extend through the front wall of the fire place and connect with the respective dampers 4 and 5 to permit them to be opened or closed as conditions may require, and a tight sliding or turning fit for the rods within the walls or where they pass through pipe or elbow 6 suffices to hold the dampers in any adjusted or closed position. Innumerable ways may be used to lock damper 5 in open or closed position but frictionally engagement of rod 22, as stated, will hold the damper in any given or set position, especially if the damper is made of relatively thin and light sheet metal.

In Fig. 8 I show a vertical outlet pipe 23 for throat member 2, and a conical deflecting cap or cover 24 supported in a tilting position at the upper end of this pipe. The dotted lines show cap 24 raised to its full extent to permit a free discharge upwardly from the fire place, and the full lines show the cap partly lowered to serve as a baffle to down-drafts. When cap 24 is fully lowered pipe 23 is closed and the conical form of the cap deflects the soot and prevents it from lodging within or dropping into the throat member of fire place.

What I regard as my invention or discovery and desire to claim, is:

35

1. A fire place or hearth having a smoke chamber, a throat member mounted within said chamber having a regulating up-draft damper and a soot protecting damper, and a false rear wall providing a soot receiving compartment open to said chamber.

40

2. A fire place or hearth having a smoke flue, a throat member fitted within said flue having a converging top terminating in a reduced discharge pipe, a regulating damper within said pipe and a soot deflecting damper at the discharge end of said pipe.

45

3. A fire place or hearth having a smoke flue, a closure plate at the entrance of said flue having a converging top terminating in a lateral discharge pipe, a regulating damper within said pipe, and a soot damper hinged at the outlet end of said pipe.

50

4. A fire place or hearth having a smoke chamber, a throat member within said chamber, a damper within said throat member, a vertical division wall extending downwardly from the rear edge of said throat member and spaced apart from the main rear wall of the fire place, and an inclined strip forming a converging soot collecting compartment behind said wall.

55

In testimony whereof I affix my signature hereto.

GEORGE A. RICHEY.
